UNITED STATES PATENT OFFICE.

JAMES STEWART, JR., OF PEEKSKILL, NEW YORK, ASSIGNOR OF TWO-THIRDS TO JAMES D. STEWART AND GEORGE T. STEWART, OF YONKERS, NEW YORK.

SEAM FOR SEWED ARTICLES.

SPECIFICATION forming part of Letters Patent No. 621,171, dated March 14, 1899.

Original application filed August 26, 1897, Serial No. 649,632. Divided and this application filed December 6, 1898. Serial No. 698,447. (No model.)

To all whom it may concern:

Be it known that I, JAMES STEWART, Jr., a citizen of the United States, residing at Peekskill, in the county of Westchester, State of 5 New York, have invented an Improved Sewing-Seam, of which the following is a specification.

This application is a division of my application, Serial No. 649,632, filed August 26, 10 1897.

The invention relates to an improvement in that style of seam produced by the sewing-stitch known as "hand-whipping," generally used for overedge-stitching and particularly 15 adapted for sewing hat-sweats and attaching the hat-sweats to hats.

In making the improved seam according to my invention a single thread is used, which in producing the seam is so manipulated that 20 the upper part of the sewing, or that part above the goods, comprises a straight line of stitches of single thread and a series of lateral stitches extending obliquely from one side thereof of double threads and a straight 25 line of stitches on the under side of the goods of double threads and lateral oblique stitches also of double threads, said stitches on the under side of the goods being coincident with the stitches on the upper side of 30 the goods. In the production of the seam the thread is first passed through the goods in the form of a loop. The goods may then be fed forward the requisite distance to form a stitch, or the needle may be advanced and 35 the thread again passed through the goods in the form of a loop, which loop passes through the loop of the first stage of the stitch. The thread is then passed through the goods in the form of a loop in an oblique 40 lateral direction to the first two stages of the stitch. The loop of this third stage or portion of the stitch passes through the loop of the second stage of the stitch. The thread is then passed through the goods at the point 45 where the second loop is formed in making the first stage of the second stitch, and the loop of this stitch passes through the loop of the third stage of the first stitch. Thus the loops of the three stages in the formation of

the stitch are locked together on the under 50 side of the goods at the juncture of the parts of the stitches which form the straight line of sewing.

In the accompanying drawings, Figure 1 represents on a magnified scale the upper 55 part or face of the seam. Fig. 2 is a similar view of the under part or back of the seam. Fig. 3 shows a hat-sweat and reed secured to a hat by the seam, and Fig. 4 shows a hat-sweat attached to a reed and the reed se- 60 cured to the hat by the improved seam.

The needle first punctures the goods, as at S, and the loop S' is formed. When the needle leaves the goods after forming this first stage of the stitch, the feeding forward of the 65 goods may occur. The needle then punctures the goods, as at S², to produce the loop S³ on the under side, said loop in its formation being passed through the loop S'. The needle punctures the goods, as at S⁴, to one 70 side of the other two punctures, and the loop S⁵ is formed and passes through the loop S³. The needle punctures the goods at S² again and another loop S' is formed, which loop passes through the loop S⁵ of the oblique lat- 75 eral part of the stitch. This second looping S' constitutes the first stage or part of the second stitch, and the operations as just described are repeated. It will be observed from Fig. 2 that there is a peculiar triangular locking of the three loops of the various 80 stages of each completed stitch, which affords great security to the seam and also provides for the flexibility of the seam before referred to, as said interlocked looped parts of the 85 stitches will be more or less tightly drawn into the goods according to the quality of the goods being acted upon.

In Fig. 3, A is the hat; B, the reed; C, the sweat, and X the line of stitching. The same 90 parts are similarly marked in Fig. 4.

Of course it should be understood that the sweat may be sewed directly to the hat without the intervention of a reed and also that the improved seam is not in any sense lim- 95 ited to the art of manufacturing hats.

I claim as my invention—

1. The herein-described seam for a sewed

article, the same comprising a fabric having a straight line of sewing composed of a single thread on the upper surface of the fabric, and a double thread on the lower surface with 5 lateral parts extending from the straight line of sewing each composed of double threads on both surfaces of the fabric, the double threads of the lateral parts on the upper surface being directly above the double threads 10 of such lateral parts on the under surface of the fabric.

2. The herein-described seam for a sewed article, the same comprising a fabric having a straight line of sewing and lateral exten-

sions from one side thereof, each alternate 15 loop of the straight line of sewing embracing a loop of one of the lateral parts of the stitches, the loops of said lateral parts of the stitches embracing the other loops of the straight line, which latter loops of the straight line of sewing 20 embrace the first-mentioned alternate loops of the straight line of sewing.

In testimony whereof I have hereunto subscribed my name.

JAMES STEWART, JR.
